CLAIM

The ornamental design for a bracelet, as shown and described.

DESCRIPTION

FIG. 1 is a perspective view of a first embodiment of a bracelet, showing our new design in a closed position;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof, showing the bracelet of FIG. 1 in an open position;

FIG. 9 is a perspective view of a second embodiment of the bracelet, shown in a closed position;

FIG. 10 is a front elevational view of FIG. 9;

FIG. 11 is a perspective view of a third embodiment of the bracelet, shown in a closed position; and,

FIG. 12 is a front elevational view of FIG. 11.

The broken lines shown in FIGS. 1-12 represent unclaimed portions of the bracelet and form no part of the claimed design.

1 Claim, 10 Drawing Sheets
